STEAM ECONOMIZING SYSTEM

Paulsen Spence, Baton Rouge, La., assignor to
 Spence Engineering Company, Inc., Walden,
 N. Y., a corporation of New York

Application October 11, 1949, Serial No. 120,705

13 Claims. (Cl. 237—9)

1

My invention relates to economizing means, as for use in a steam-operated system in which a high-pressure-operated means is to be operated relatively intermittently and in which a low-pressure-operated means is to be operated relatively continuously.

It is an object of the invention to provide an improved system of the character indicated.

It is another object to provide an improved means for maintaining continuous operation of low-pressure-operated means in spite of intermittent operation of high-pressure-operated means from the same boiler plant.

It is a specific object to provide means whereby a low-pressure-operated means may be operated by exhaust steam from high-pressure-operated means as long as the high-pressure-operated means is operative, but in which a regulated flow of reduced-pressure steam may be automatically supplied to said low-pressure-operated means during periods in which the high-pressure-operated means is not functioning or in which the quantity of exhaust steam supplied thereby is insufficient.

Other objects and various further features of the invention will be pointed out or will occur to those skilled in the art from a reading of the following specification in conjunction with the accompanying drawings. In said drawings, which show, for illustrative purposes only, preferred forms of the invention:

Fig. 1 is a simplified layout schematically showing a system to which my steam-economizing system has been applied; and

Figs. 2 and 3 schematically show alternative forms of the invention.

Briefly stated, my invention in a preferred form contemplates application to a steam-operated plant in which high-pressure-operated means, such as a steam engine to run a juice extractor, is operated intermittently and in which low-pressure-operated means, such as evaporating heaters, are to be run more or less continuously. The low-pressure-operated means for heaters may be connected in the exhaust line from the steam engine, and damper means further down the exhaust line may assure the needed low-pressure steam in the heaters as long as the engine is operating. During periods when the steam engine is not operating or in which the back pressure is insufficient for the heaters, I provide a by-pass connection between the high-pressure side of the steam engine and the heaters, and this by-pass connection may include pressure-reducing means to provide the desired

2

low-pressure steam for the heaters. In order that the by-passed steam shall not be wasted, I provide means for automatically closing the damper means during idle periods for the steam engine; and the pressure-reducing system may be interlocked with the damper means, or with the means for controlling the damper means, so as not to by-pass steam until the damper means has been closed. The damper means may be closed by pressure-responsive means responsive to back pressure from the steam engine, and the pressure-reducing system may be pilot controlled. In one form to be described, the pilot-controlled reducing valve is interconnected with the pressure-responsive means for controlling the damper; in another form, the damper is mechanically interlocked with the pilot control for the pressure-reducing system; and, in the third form, the pilot control is electrically interlocked with the damper.

Referring to Fig. 1 of the drawing, my invention is shown in application to a steam-operated plant such as a cane-sugar mill. The plant may include means (not shown) for supplying high-pressure steam in an inlet line 5 to a steam engine 6, which engine 6 may be for operation of a juice extractor or the like, for relatively short intermittent periods. The exhaust steam from the engine 6 may pass through an outlet 7 to a stack 8. The mill may further include low-pressure-operated means, such as heaters for an evaporating system, to be run more or less continuously; and the heaters (not shown) may be supplied via a line 9, connected to exhaust line 7 for the engine 6. In order to assure sufficient low pressure for operation of the heaters via line 9, a damper in the form of a lever-operated damper valve 10 may be interposed between the line 9 and the exhaust stack 8.

In accordance with a feature of the invention, the damper valve 10 may be operated to assure continuous supply of low-pressure steam to the heaters in line 9, even during shut-down periods for the engine 6. Such controlling means may include pressure-responsive means 11 connected in the exhaust line 7 or in the heater line 9 (as shown at 9'), and in the form shown the pressure-responsive means 11 is connected to operate the reversing valve 12' of a double-acting fluid-pressure-operated actuator 12. The actuator 12 may be operated by water pressure, and the usual service pressure will ordinarily be quite adequate. Upon a drop in pressure of steam supplied to the heater, the pilot 11 may position the reversing valve 12' to cause the actuating piston 13 of the

actuator 12 to be driven upwardly, and thus to permit a lowering of the lever 14 for the damper 10, in order to close the damper 10. Upon a rise in pressure in the line 9, as when the engine 6 is again operated, the pressure-responsive means 11 will be understood to reverse the operation of the actuator 12, in order once more to open the damper 10.

In accordance with a further feature of the invention, I provide a means for by-passing the steam from the high-pressure line 5 to the heater line 9 whenever the heater-supply pressure has dropped to a given minimum value, which may be the low pressure at which the damper 10 is closed. The by-pass connection may include pressure-reducing means which preferably supplies steam at a sufficiently low pressure as not to open the damper 10. The pressure-reducing means may include a main valve 15 having an inlet line 16 connected to the high-pressure line 5 and an outlet line 17 connected to the exhaust line 7 of the engine 6 of the damper 10. The pressure-reducing means may be pilot controlled, as disclosed more specifically in my Patent 1,995,949, dated March 26, 1935. The main valve 15 may be diaphragm-actuated, and pressures over the diaphragm may be derived from a line 18 connected to the high-pressure side of the valve 15 and including a pressure-responsive pilot 19. The pilot may derive its control pressures from a line 20 connected to the low-pressure end of the by-pass connection, as at the pipe 17; and the low-pressure side of the pilot 19 may be connected by line 21 to the diaphragm, and by a bleed connection 22 to the low-pressure side of the main valve 15.

In the form shown, I employ a further pressure-operated pilot 23 in series with the pilot 19 in order to control the on-off operation of the pressure-reducing by-pass connection. Regulating-valve control by means of a plurality of pilots in series is shown and described in detail in my Patent 1,987,032. The pressure-responsive means of pilot 23 may be a water-actuated diaphragm connected, as by line 24, to one of the ends of the double-acting actuator 12. The connection of pilot 23 to the actuator 12 is preferably such that the pilot 23 will be opened upon a supply of damper-closing water pressure to the actuator 12. Only upon loss of such closing pressures, as when the steam engine 6 is again operated (so as to open the damper 10) will the springs 25 of pilot 23 be effective to close off the by-pass connection.

In Fig. 2, I show an alternative embodiment of my invention for substantially the same use and application as has been described above in connection with Fig. 1. In Fig. 2, however, the opening and closing of the by-pass connection is effected by a mechanical connection between a pilot valve 30 and the damper 10. Such mechanical connection may include a link 31 between the lever 14 for the damper valve 10 and a rocker 32 for actuating the pilot 30. It will be understood that, whenever the pressure-responsive means 11-12 demands a closure of damper 10, as after the engine 6 is shut down, the lever 14 will be displaced downwardly and at the same time the pilot 30 will be opened in order to open the pressure-reducing by-pass connection and thus to maintain continued supply of low-pressure steam, as needed, to the evaporator heaters.

In Fig. 3, I show another alternative arrangement according to the invention. In Fig. 3, however, I employ electrically controlled interlocks for closing and opening the pressure-reducing by-

pass connection in accordance with the operation and shut down of the engine 6. In Fig. 3, I employ a solenoid-operated pilot valve 35 in series connection with the pilot 19 of the pressure-reducing means, and a switch 36 may be in electrical-controlling relation with the solenoid of valve 35. In the form shown, the switch 36 is positioned to be actuated when the damper lever 14 reaches a downward position, which may be representative of a closed damper. It will then be understood that only upon closure of the damper may the by-pass connection 16-17 be opened to supply reduced pressure to the heaters. When the engine 6 is started again, the back pressure will rise so as to operate the actuator 12 and thus to open the damper 10. This opening of the damper 10 will be evidenced by a lifting of the lever 14 and, as soon as the lever 14 is lifted from its bottom position, the switch 36 may be effective to close off the by-pass connection 16-17.

It will be seen that I have described a relatively simple system for assuring the economical supply of low-pressure steam to a continuously operated low-pressure system, even during extended shut-down periods for a high-pressure-operated means connected to the same steam-supply system. My economizing system may be adjusted to operate only when the damper is closed and therefore to utilize all the by-passed steam.

While I have described my invention in considerable detail for the preferred forms shown, it will be understood that modifications may be made within the scope of the invention as defined in the appended claims.

1 claim:

1. In a steam-economizing system of the character indicated, high-pressure-operated means to be intermittently operated, low-pressure-operated means to be more continuously operated, said high-pressure-operated means including an inlet for high-pressure steam and an exhaust outlet, a damper in said exhaust outlet, said low-pressure-operated means being connected to said exhaust outlet between said damper and said high-pressure-operated means, said damper including pressure-responsive actuating means responsive to pressure supplied to said low-pressure-operated means and effective to close said exhaust outlet upon a drop in exhaust pressure below a given value, a by-pass connection including pressure-reducing means between the inlet to said high-pressure-operated means and said low-pressure-operated means, and by-pass-enabling means connected to said actuating means for rendering said pressure-reducing means effective to by-pass steam to said low-pressure-operated means upon a closure of said damper and for cutting off said by-pass connection upon an opening of said damper.

2. In a steam-economizing system of the character indicated, high-pressure-operated means including an inlet for steam at relatively high pressure and an exhaust outlet, a damper in said exhaust outlet, low-pressure-operated means connected to said exhaust outlet between said high-pressure-operated means and said damper, pressure-responsive-damper-actuating means in said exhaust outlet and connected to said damper to close said damper upon a drop in back pressure below a given value, a pressure-reducing by-pass connection between the high-pressure inlet to said high-pressure-operated means and said low-pressure-operated means, said by-pass connection including on-off control means connected to said damper-actuating means for open-

ing said by-pass connection upon sufficient drop in back pressure to close said damper and for closing said by-pass connection upon a rise in back pressure sufficient to open said damper.

3. A system according to claim 2, in which said means opening said by-pass connection is a pressure-operated valve operative upon operation of said pressure-responsive means.

4. A system according to claim 2, in which said means opening said by-pass connection is a valve mechanically interconnected with said damper to open said valve upon closure of said damper.

5. A system according to claim 2, in which said means opening said by-pass connection is an electrically-operated valve electrically connected to a switch operated upon closure of said damper, whereby said by-pass connection may not be opened until said damper has been closed.

6. In a steam-economizing system of the character indicated, high-pressure-operated means including an inlet for high-pressure steam and an exhaust outlet, a damper in said exhaust outlet, low-pressure-operated means connected to said exhaust outlet between said high-pressure operated means and said damper, pressure-responsive double-acting actuating means for said damper and connected to said exhaust outlet to close said damper upon a drop in back pressure below a given value, a by-pass connection from the high-pressure inlet side of said high-pressure-operated means to said low-pressure-operated means, said by-pass connection including a pressure-operated valve connected to one side of said double-acting pressure-responsive means, said last-mentioned connection being such that said by-pass connection is opened upon closure of said damper and closed upon opening of said damper.

7. A system according to claim 6 in which said by-pass connection includes pressure-reducing means providing a reduced pressure below said given value, whereby said damper may remain closed as long as said by-pass connection is effective to supply by-passed steam.

8. In a steam-economizing system of the character indicated, high-pressure-operated means including an inlet for high-pressure steam and an exhaust outlet, a damper in said exhaust outlet, low-pressure-operated means connected for supply from said exhaust outlet at a point between said damper and said high-pressure operating means, a by-pass connection between said high-pressure inlet and said low-pressure-operated means, said by-pass connection including a pilot-controlled regulating valve, pressure-responsive means responsive to back pressure and connected to close said damper upon a drop in back pressure below a given value, and pilot-valve means in series connection with the pilot of said regulating valve and effective to operate said regulating valve upon a closing of said damper.

9. In a steam-economizing system of the character indicated, steam-operated means including an inlet and an exhaust outlet, a damper in said exhaust outlet, heater means connected to said steam-operated exhaust outlet between said means and said damper, pressure-responsive damper-actuating means in said exhaust outlet between said steam-operated means and said damper and connected to said damper to close said damper upon a drop in back pressure below a given value, a by-pass connection between the inlet to said steam-operated means and said

heater means, said by-pass connection including on-off control means responsive to exhaust pressure upstream from said damper to open said by-pass connection upon a sufficient drop in exhaust pressure to effect closure of said damper, said control means being further effective to close said by-pass connection upon a sufficient rise in exhaust pressure to effect an opening of said damper, whereby live steam may never be vented by said damper.

10. In a steam-economizing system of the character indicated, steam-operated means to be operated intermittently and including an inlet for relatively high-pressure steam and an exhaust outlet, damper means for said exhaust outlet and including pressure-responsive direct-actuating means therefor, auxiliary means to be operated by steam at relatively low pressure, said auxiliary means being connected to said exhaust outlet between said first-mentioned means and said damper means, said pressure-responsive direct-actuating means being connected for response to a drop in pressure at the exhaust side of said first-mentioned means and effective to close said damper means, pressure-reducing means between the high-pressure side of said first-mentioned means and said auxiliary means, and on-off control means for said pressure-reducing means and directly connected for operation by said direct-actuating means, whereby said pressure-responsive direct-actuating means may assuredly enable said pressure-reducing means upon a sufficient drop in pressure to close said damper means, and whereby said pressure-reducing means may be effectively shut off upon a sufficient rise in pressure to open said damper means, so that live steam may never be vented by said damper means.

11. An economizing system according to claim 10, in which said on-off control means includes biasing means biasing said control means against an enabling of said pressure-reducing means until attainment of a sufficiently low exhaust-outlet pressure to assure closure of said damper means, whereby said damper means may not begin to open until after said pressure-reducing means has been cut off.

12. An economizing system according to claim 11, in which said control means is a pressure-responsive control valve, and in which said biasing means is a spring stressed against a pressure-responsive element of said control valve.

13. An economizing system according to claim 10, in which said on-off control means is connected to enable said pressure-reducing means only during maintenance of a sufficiently low exhaust-outlet pressure to assure closure of said damper means, whereby said damper means may not begin to open until after said pressure-reducing means has been cut off.
